UNITED STATES PATENT OFFICE.

MONTGOMERY H. JOHNSON, OF UTICA, NEW YORK.

JUNCTION OR FUSE BOX.

SPECIFICATION forming part of Letters Patent No. 699,181, dated May 6, 1902.

Application filed December 28, 1901. Serial No. 87,517. (No model.)

To all whom it may concern:

Be it known that I, MONTGOMERY H. JOHNSON, of Utica, in the county of Oneida and State of New York, have invented certain new and useful Improvements in Junction or Fuse Boxes; and I do hereby declare that the following is a full, clear, and exact description of the invention, which will enable others skilled in the art to which it appertains to make and use the same, reference being had to the accompanying drawings, and to the letters of reference marked thereon, which form part of this specification.

The object of my present invention is to provide a junction or fuse box having a bottom or base compartment and a removable tablet in which the electrical devices can be mounted and to which access may be readily and conveniently had.

In the drawings, Figure 1 shows a plan view of my fuse or junction box with the cover removed. Fig. 2 shows a section taken on line A B of Fig. 1. Fig. 3 shows a section taken on line C D of Fig. 1. Fig. 4 shows in plan view a modified form of construction. Fig. 5 shows a longitudinal section of this construction, and Fig. 6 shows a cross-section taken on line E F of Fig. 5.

Referring to the reference letters and figures in a more particular description of the device, 1 indicates the walls of the box or casing, and 2 the bottom of the same. The interior of the box is lined as to the sides with liners 3 of insulating material, as slate, and the bottom is also provided with a liner 4 of similar material. Secured to the inner wall of the box is a rib or flange 5, constituting one part of the tablet on which the electrical devices are secured. In the same plane there is also supported and secured by means of the supports or straps 6 the removable portion of tablet 7. Both portions of the tablet are of insulating material. The tablet occupies such a position in the box as to provide the space 8 between the tablet and the bottom of the box. The box and electrical devices shown therein are arranged for what is known as a "three-wire system," although this is not material to my invention. As shown, there are two openings through one end of the box into the space between the bottom and the tablet (indicated, respectively, by m and

n) and in the other end of the box a single opening, indicated by o.) In the sides of the box there are openings, (indicated by r.) 55 According to the arrangement of the conductors and apparatus shown the entrances in the ends of the box are used for the main leads, while the openings in the sides of the box are employed for the passage of the wires 60 of the local circuits, as in a house-lighting system. The conductors or connections for bringing the connections to the surface of the tablet are the same in both the main leads and the subcircuits, and the description of 65 one will suffice for all. On the fixed or frame portion of the tablet is secured by one of its end branches the Z-shaped connecting-piece 9. The body portion of this piece passes through an opening on the line of separation 70 between the fixed and removable portions of the tablet, and at the lower end the inwardly-projecting end of the piece 9 takes a position beneath or behind the removable portion 7 of the tablet, and to this 75 end may be secured by a screw 11 or in any other suitable manner the end of the wire or conductor 12. While the wire 12 as shown in the drawings is carried to the nearest and most convenient opening through the wall of 80 the box, it is evident that it may be carried across the box or to any regularly or irregularly located opening, and a considerable surplus length of wire can be accommodated in the space 8 beneath the tablet. On the face 85 side of the tablet there is provided on the piece 9 a binding-post, as 10, which may also include a screw that will secure the piece 9 in position. On the removable portion of the tablet 7 are located the so-called "bus-bars," 90 (indicated by a, b, and c, respectively.) These may be connected in the construction as shown to the positive, negative, and neutral wires, respectively. Each bus-bar is provided with a main binding-post, as 15, by 95 means of which the bus-bars are connected with the main leads. The bus-bars are also provided with a series of other binding-posts (indicated by 16) and adapted to accommodate the connections to the local or sub circuits. The binding-posts 16 and 10 are located and arranged in pairs with a considerable space between them, which is known as the "fuse-gap." The fuses (indicated by x) cross

the fuse-gap and are secured at their respective ends by binding-posts 10 and 16. It will be noted that the line of separation between the fixed and removable portions of the tablet is 5 in the fuse-gap; also, that while a considerable space (indicated by *w*) is shown in the drawings between the frame portion 5 and the main portion 7 of the tablet this space can be reduced simply to a line of separation, 10 in which case the body portion of the connectors 9 would be inlet either in the frame 5 or the body 7.

When the fuses are removed, the body portion 7 of the tablet can be removed after taking out the securing-screws 6^a at the corners. 15

When the body portion of the tablet is removed, free access can be had to all the wires and connections in the base of the box, including the securing-screws or other attaching devices, which are all located directly behind or beneath the removable portion of the tablet. Access is also had to the entire length 20 of the connecting-pieces 9.

In the modified form of construction shown 25 in Figs. 4, 5, and 6 the same form of box 1, with bottom 2, side liners 3, and bottom liner 4, are employed; also, the same fixed frame portion of tablet 5 and removable portion 7, supported by straps 6. In the construction, 30 however, shown in Figs. 4, 5, and 6 the bus-bars (indicated by *a'*, *b'*, and *c'*) are located in planes one above the other. The bus-bar *a'* is supported by a bridge 20, which also constitutes a portion of the electrical connection 35 and is provided with binding-posts upon either side, and the bus-bar *b'* is supported by bridge 21, which also constitutes a part of the electrical connection and is provided with binding-posts upon either side. The 40 bus-bar *c'* lies flat upon the face of the tablet, or nearly so, and is also provided with lateral branches 22 and 23 and binding-posts at their extremities. In the case of this construction the bars *a'* and *b'* may be attached to the positive and negative leads, respectively, while the bar *c'* is attached to the neutral wire of a three-wire system. By locating the bus-bars in planes one above the other I am enabled to economize space and use a 45 box or casing of smaller dimensions than in the construction illustrated in Figs. 1 to 3, inclusive.

In the modified form of construction the same **Z**-shaped connecting-pieces 9 are em-

ployed as in the construction previously described. 55

What I claim as new, and desire to secure by Letters Patent, is—

1. The combination in a fuse or junction box of the box or casing, an internal frame 60 secured in the box above the bottom, a removable tablet supported within the said frame, entrances for electrical connections into said box below the tablet, fixed binding-posts on said frame electrically connected 65 with the conductors, "bus-bars" and corresponding binding-posts on the removable tablet and removable fuses, substantially as set forth.

2. The combination in a fuse or junction 70 box of the casing, an internal frame secured to the side of the box above the bottom, a removable tablet supported within the frame, "bus-bars" and binding-posts arranged on said tablet, corresponding binding-posts arranged on said frame, **Z**-shaped connecting-pieces extending from the binding-posts through the line of separation between the frame and the tablet into the space beneath the tablet, entrances for electrical conductors 80 into the space beneath the tablet and means for connecting the conductors to said **Z**-shaped connecting-pieces arranged beneath the tablet, substantially as set forth.

3. The combination in a fuse or junction 85 box of a casing, a two-part tablet supported above the bottom of said casing, one of said parts being removably secured and the other part fixed in the casing, entrances into said casing for electric conductors between said 90 tablet and bottom of casing, binding-posts on said fixed portion of tablet and corresponding binding-posts mounted on the removable portion of the tablet, electrical distributing connections mounted upon and connected with 95 the binding-posts on said removable portion and fuse-wires connecting said two sets of binding-posts and spanning the line of separation between the fixed and removable portions of tablet, substantially as set forth. 100

In witness whereof I have affixed my signature, in presence of two witnesses, this 14th day of December, 1901.

MONTGOMERY H. JOHNSON.
